Specification of Letters Patent.

Patented Feb. 10, 1920.

Application filed April 29, 1915. Serial No. 24,685.

To all whom it may concern:

Be it known that I, THOMAS LUND, a citizen of the United States, residing at Beverly, in the county of Essex and State of Massachusetts, have invented certain new and useful Improvements in Heel-Builders; and I do hereby declare the following to be a full, clear, and exact description of the invention, such as will enable others skilled in the art to which it appertains to make and use the same.

This invention relates to a machine in which lifts or layers of leather, leather-board, or other suitable material are assembled to form heel-piles or heels.

In machines of the kind in question it has heretofore been proposed to employ a series of receptacles which hold heel-lifts graded as to size, and to provide automatic mechanism for withdrawing lifts from the several receptacles in order, and for assembling these lifts together, thus building up a heel-pile of the required form.

The present invention relates to machines of the same general type, but is designed to produce a machine in which heel-piles may be produced from suitably graded blanks or lifts, either automatically or at the will of the operator, by a selective operation such that the number of lifts withdrawn from the graded supply, and the sizes of the lifts so selected, may be readily varied or predetermined, thus permitting the production of heel-piles of different sizes and styles from the same supply, that is, without the necessity of changing the sizes of the lifts in the several receptacles. This constitutes one object of the invention.

To the foregoing end it is proposed to employ, in connection with a series of containers or receptacles holding lifts of graded sizes, mechanism for withdrawing and assembling the lifts, this mechanism being operable, either automatically or under manual control, to withdraw lifts not necessarily in the order of the series of receptacles but in other orders which may be mechanically determined in the case of an automatically operating machine, or selected at the will of the operator in a manually controlled machine.

Another object of the invention is to produce a machine in which the heel-lifts or blanks are held in vertical stacks in the supply-receptacles, but in which they are

assembled against a vertical holder, that is, with the lifts lying in vertical planes. To this end the invention includes an arrangement in which the means which transfer the lifts from the supply-receptacles to the pile-holder are arranged to impart a quarter-turn to each lift, in connection with the transferring operation.

Other objects of the invention, and the features of construction by which they are attained, will be pointed out hereinafter in connection with the description of the illustrated embodiment of the invention.

The preferred form of the invention is illustrated in the accompanying drawings in which:

Figure 1 is a plan of a machine embodying the present invention;

Fig. 2 is a left-hand side-elevation of the machine;

Fig. 3 is a left-hand side-elevation of a portion of the controlling-mechanism of the machine, on a larger scale than the preceding figures;

Fig. 4 is a side-elevation, showing in detail the transfer-mechanism and a portion of the ejecting-mechanism;

Fig. 5 is a plan, on a larger scale than Fig. 4, showing particularly the transfer-mechanism;

Fig. 6 is a partial vertical section on the line 6—6 of Fig. 3;

Fig. 7 is a rear-elevation, partly in section, showing in detail a part of the trip-mechanism for controlling the transfer-mechanism;

Fig. 8 is a horizontal section showing a portion of the selecting-mechanism;

Fig. 9 is a detail, in left-hand side-elevation and partly in section, showing a portion of the controlling-mechanism; and

Fig. 10 is a detail from Fig. 2 on a larger scale.

The invention is illustrated as embodied in a heel-building machine adapted to hold heel-blanks of eight graded sizes and to assemble these heel-blanks in a number and order which may be determined either by manually operable means or by automatic means.

The machine is provided with a series of blank-receptacles 10, shown particularly in Fig. 2, a plate or holder 11 against which the blanks are assembled, a transfer-mechanism 12 by which the heels are removed

105

110

from the receptacles and carried to and assembled on the holder 11, pasting-mechanism 13 by which paste is applied to the blanks during the transferring operation, 5 and a controlling-means or key-mechanism which may include a series of finger keys 14, by which the selecting action of the machine may be controlled either automatically or at the will of the operator.

10 The construction of the supply-receptacles is shown particularly in Figs. 1 and 2. Each receptacle has two-side-walls 15 which are hinged, at the rear, on a pivot-rod 16 mounted in lugs in an elongated upright 17. The 15 blanks or layers of materials, referred to hereinafter simply as "lifts" in an inclusive sense, are held in a vertical stack between the side-members, and are retained, in front, by inwardly projecting flanges 21 on the side-members. In order that each receptacle may be adjustable to some extent to adapt it to receive lifts of different sizes, a screw-threaded rod 18 is pivoted to each side-member and passes rearwardly 25 through the upright 17, a spring 19, coiled around the rod, is interposed between the upright and the corresponding side-member, and an adjusting-nut 20 is screwed on the rear end of the rod. By turning the nuts 20 30 the side-members may be swung toward or from each other and fixed in their adjusted positions, thus adapting the receptacle to receive lifts of different widths.

Each stack of lifts is supported, at the 35 bottom, by a thin plate 22 projecting forwardly from the upright 17, and, as shown in Fig. 2, the plate 22 is spaced below the lower edges of the side-members at a sufficient distance to permit the lowermost lift 40 of the stack to be withdrawn, by a horizontal or edgewise movement, at the front of the receptacle.

The construction of the transfer-mechanism indicated generally, in Fig. 2, by the 45 number 12, is shown particularly in Figs. 4 and 5. A plate 23 is carried by a block 24 fixed on the upper end of a plunger 25. The lift which is transferred lies flat upon this plate, with its breast-edge against two lugs 50 26 which project upwardly from the front edge of the plate. In order to center the lift and clamp it in position on the plate while it is being applied to the holder 11, two clamping-pins 27 are mounted upon bell- 55 crank levers 28, these levers being arranged to swing below the plate 23 on pivot-screws 29, and the pins project upwardly through curved slots in the plate, as shown in Fig. 5. The adjacent ends of the two levers are 60 arranged in overlapping position, and have coincident elongated slots engaged by a pin 31. This pin projects upwardly from a slide-rod 32, which moves horizontally through the block 24. A spring 33, coiled about the 65 rod and engaging a shoulder thereon, tends

to move the rod rearwardly, thus causing the levers 28 to be swung in a direction to force the pins 27 against opposite edges of the lift, and, since the movement of the pins is simultaneous and equal, the lift is thus 70 accurately centered on the plate 23, as well as being clamped between the pins 27 and the lugs 26.

The movements of the slide-rod 32 are controlled by a lever 35, which is pivotally 75 mounted on the rear of the plunger 25, the upper end of this lever being articulated with the rod 32, while its lower end is provided with a beveled surface 36 and a tooth 37. This surface and tooth coöperate with 80 an oppositely beveled tooth 34 at the upper end of a sleeve 38 in which the plunger 25 is mounted to slide vertically. The sleeve 38 is provided, at its upper end, with trunnions 39 having bearings in lugs 40 projecting upwardly from a slide 41. This slide travels horizontally upon a guideway 42. A spring 43, coiled about one of the trunnions 39, tends to rock the sleeve 38 in a counter-clockwise direction, as seen in Fig. 90 4, and as this movement is arrested by the engagement of the lower end of the sleeve with a part 78, hereinafter described, the spring normally holds the sleeve in the upright position shown in Figs. 2 and 4. Within the sleeve 38 a spring 44 is coiled around the plunger 25, and this spring engages, at its upper end, a shoulder on the plunger and forces the plunger upwardly, this upward movement being limited, however, by 95 stop-nuts 45 on the lower end of the plunger.

The transfer-mechanism is brought beneath one or another of the supply receptacles by a rearward horizontal movement of the slide 41 upon the guideway 42 (to the 105 left in Fig. 2), thus bringing the plate 23 directly beneath the receptacle. At this time the plunger 25 is somewhat depressed from the position shown in Figs. 2 and 4, being held so by the engagement of the tooth 37 on 110 the lever 35 with the tooth 34 on the sleeve 38. In the same way the lever 35 is held with its upper end in a forward position, so that the slide-rod 32 is held in a forward position and the clamp pins 27 are in their 115 retracted or outer position. During the last part of the rearward movement of the slide, however, the upper end of the lever 35 is brought into engagement with an adjustable stop-screw 46, whereby the lever is swung in 120 a direction to disengage the teeth 34 and 37, thereby permitting the spring 44 to raise the plate 23 against the plate 22 and thus bring the clamp-pins 27 into a position in which they span the edges of the lowermost 125 lift in the stack. Upon the succeeding forward movement of the transfer-mechanism the upper end of the lever 35 is moved out of coöoperative relation with the stop-screw 46 so that the spring 33 is free to move the 130

slide-rod 32 and close the clamp-pins upon the lift. As the forward movement progresses the lift held between the lugs 26 and pins 27 is removed from the supply-receptacle.

As the parts move forwardly, to transfer the lift to the holder 11, the lift is swung downwardly and forwardly into the vertical position which it will occupy on the holder.

- 10 For this purpose a cam 47 is mounted on the guideway 42, in position to coöperate with a cam-roller 48 mounted at the front of the sleeve 38, as shown in Fig. 4. The guideway 42 is slotted in its rear portion, to permit the 15 sleeve to move through it in the vertical position of Fig. 4, but during the forward movement of the parts the roller 48 encounters the curved rear end of the cam, and the sleeve is thus rocked about the trunnions 39 20 to a horizontal position, thus swinging the plate 23 into a vertical position, and at the completion of the forward movement the lift is pressed either against the holder 11, or against the surface of a lift which has 25 been previously applied to the holder, with a pressure which is regulated by the spring 44. At the same time the plunger 25 is pressed inwardly in the sleeve 38, thus bringing the lower end of the lever 35 into 30 coöperative relation with the tooth 34 on the sleeve, whereby the clamp-pins are disengaged from the lift and the plunger is locked in its retracted position. The lift is thus released, and upon the succeeding rearward movement of the transfer-mechanism 35 is left in position on the holder.

The first lift transferred to the holder 11 is temporarily retained thereon by means of short points 50 projecting from the face of 40 the holder, while the succeeding lifts are secured to the first lift, and to each other, by paste which has been applied to them by the pasting-devices indicated generally in Fig. 2 by the number 13.

45 The illustrated pasting-devices comprise a roller 51, (Fig. 2) which is journaled in slide-rods 52 movable vertically in brackets 53 projecting upwardly from the frame of the machine. Paste is supplied to the surface of the roller 51 from a reservoir 54 supported, above the roller, on the slide-rods 52. The roller is normally supported at such a level that it will be engaged by the upper surface of a lift carried beneath it by the 50 movement of the transfer-mechanism.

In order to prevent the application of paste to the first lift which is applied to the holder 11, means are provided for raising the paste-roller 51 automatically out of operative position when the first lift-receptacle is in operative position. The lower end of one of the slides 52, by which the paste-roller is supported, rests on the forward end of a lever 262 which is pivoted on one of the 60 brackets 53, as shown in Fig. 2, and the rear

arm of the lever bears normally against a stop-screw 266 which is adjustable to vary the height of the paste-roller when it is in its operative position. An arm 270 projects from the right-hand end of the upright 17, 70 as shown in Fig. 1, and a cam-block 268 is fixed to this arm, in such a position that the cam-block will engage and depress the rear end of the lever 262 when the first lift-receptacle is in operative position, thus causing the lever to lift the paste-roller and prevent it from being engaged by the lift withdrawn from the receptacle. In case it be desired to commence the building of the heel-block with a lift from any of the other receptacles, the cam-block 268 may be moved to and fixed in any suitable position on the upright 17.

The means for actuating the transfer-mechanism comprise a power-shaft 56 which 85 is journaled horizontally in the frame of the machine, and through which power is transmitted to all parts of the mechanism. This shaft carries a pulley 58, by which it may be connected with any suitable source of power. 90 The pulley rotates freely on the power-shaft, but a pinion 60 is fixed to the pulley (Fig. 8), and this pinion drives a gear-wheel 62 (Fig. 1) which turns loosely on a countershaft 64 journaled in the frame of the machine. The countershaft is provided with a crank 66 (Fig. 6) connected, through a slide-block 68 (Fig. 3) with a lever 70 having a vertical guideway in which the block 68 slides. This lever is mounted, at its lower end, on a pivot 72 carried by a bracket 74 depending from the frame of the machine. A second slide-block 76 (Fig. 4) is pivoted to the upper end of the lever 70, and this block moves in a guideway 78 depending 105 from the slide 41. Owing to this arrangement each rotation of the countershaft 64 causes the slide 41 and the other parts of the transfer-mechanism to perform a complete cycle of operations as above described. The 110 countershaft 64 is not normally in rotation but is controlled by means hereinafter described, including a Horton clutch, by which it may be connected intermittently with the gear-wheel 62.

115 Since the path of movement of the transfer-mechanism is fixed, the selective coöperation of this mechanism with the different lift-receptacles is accomplished by moving the receptacles transversely to bring them successively into operative position for the removal of the lifts. For this purpose the upright 17 is mounted on a slide 80 (Fig. 2), which moves in a dove-tailed guideway 82 on the frame of the machine. The slide is 120 moved by the engagement of a roller 84, mounted on the bottom of the slide, with a cam-path 85, in the form of a helical groove, cut in the surface of a cylinder 86. (See Fig. 1). This cylinder is mounted on a shaft 125 130

88 (Fig. 2) having bearings in the frame of the machine. By rotating the cylinder to a sufficient degree any one of the lift-receptacles may be brought into operative position.

The cylinder 86 is rotated, in the performance of the selective operation, with a step-by-step movement, by means of a Geneva stop-mechanism. This mechanism comprises the usual teeth and locking surfaces 90 (Fig. 2), at the left-hand end of the cylinder, which coöperate with corresponding teeth and surfaces on a pinion 94 mounted on the power-shaft 56. For each rotation of the pinion the cylinder is turned through a space sufficient to cause the slide 80 to move one of the lift-receptacles out of position and the next adjacent receptacle into position for coöperation with the transfer mechanism.

The cam-path 85 passes helically around somewhat more than half of the cylinder in one direction, and then returns in the opposite direction so as to move the slide 80 back to its original position, and since this return-movement is made after all of the lift-receptacles have been brought successively into operative position, it is performed completely without interruption. For this purpose the cam-cylinder is provided, at its left-hand end, with a segmental gear 92 which coöperates with a pinion 96 mounted on the power-shaft 56 and integral with the pinion 94, as shown best in Fig. 8.

The power-shaft is not normally rotated by the pulley 58, but is provided, as shown in Fig. 8, with a toothed clutch-member 98, and a second clutch-member 100 (see also Fig. 3) is mounted on the shaft, with a key-and-groove connection, so that it may be thrown into and out of engagement with the member 98. A spring 102 tends to engage the clutch-members, but the member 100 is controlled by a forked lever 104 which is mounted on a pivot 106 (Fig. 3) on the frame of the machine.

The clutch just described is controlled, through the lever 104, by means which may be actuated by the finger keys (Fig. 1) so as to cause the cylinder 86 to be rotated to bring the several lift-receptacles selectively into operative position. For this purpose the lever 104 coöperates, at its upper end, with a beveled block 108 (Figs. 1, 2 and 3) which is fixed on a slide-rod 110. This rod moves through bearings 112 and 114 on the lever 116, which is mounted at its forward end on a pivot 118 on the frame of the machine. The rear end of the rod 110 coöperates with a segment 120 (Fig. 2) fixed to rotate with the cylinder 86, this segment having a series of stepped shoulders 122.

The key-mechanism may comprise, for manual operation, a plurality of finger-keys 14 each of which is carried by a key-lever

124, these levers being all pivoted loosely upon a rock-shaft 126 (Fig. 3) mounted transversely in the frame of the machine. Projecting upwardly from each key-lever is a lifter-arm 128, and springs 130, connecting each lifter-arm with the frame of the machine, hold the key-levers and the keys normally in raised position.

The lever 116 forms one member of a yoke-like frame having an arm 131, as shown in Fig. 1, parallel with the lever 116, and also pivoted on the rod 118. Between the lever 116 and the arm 131 a rod 132 extends, this rod being provided with a roller-sleeve 133 which is located adjacent the upper ends 80 of the lifter-arms 128. Whenever any one of the key-levers is depressed the corresponding lifter-arm moves forwardly beneath the roller 133 and engages and raises this roller, thus swinging upwardly the lever 85 116, and as the lifter-arms are of graduated lengths, as shown in Figs. 3 and 9, the distance through which the lever is raised depends upon which key-lever is actuated.

The rising movement imparted to the lever 116 as just described causes the rear-end 90 of the slide-rod 110 to be lifted out of engagement with any one of the shoulders 122 on the segment 120 with which it may be at the time in engagement, thus releasing the 95 rod for rearward longitudinal movement. Such movement is then at once produced by a spring 136 which is coiled around the rod and engages, at one end, the bearing 112, and at the other end the beveled block 108. 100 this movement being limited by a stop-collar 138, near the forward end of the rod, which is brought into engagement with the bearing 112.

When the block 108 is moved rearwardly 105 with the rod 110 it releases the upper end of the clutch-lever 104, so that the clutch spring 102 can engage the clutch-member 98 and 110 100, thereby causing the pinions 94 and 96 to be actuated, and the cylinder 86 to be rotated 115 in the direction of the arrow in Fig. 2. The extent of this rotation depends upon the degree to which the lever 116 and the rod 110 have been raised. If they have been raised only enough to clear one of the shoulders 115 122, the rotation of the cylinder continues through one rotation of the Geneva pinion 94, but near the end of this rotation the next adjacent shoulder 122 engages the end of the rod 110 and thrusts the rod forwardly, thus 120 operating the clutch-lever 104 and causing it to again disengage the clutch. This is what occurs when the operator has pressed a key next adjacent to the one which was previously pressed, so that the lever 116 has 125 been raised only through a space corresponding to the difference in length between two adjacent lifter-arms 128, but if the key which has been pressed is more remote from the last key which was pressed the cylinder may 130

be rotated by more than one rotation of the pinion 94, thus causing a selective movement of the lift-receptacles by which one or more of these receptacles is moved idly past the operative position. In this manner the operator may cause the machine to select lifts either from all the receptacles in succession or from only a portion of these receptacles and in any desired sequence.

10 In order that it may be unnecessary for the operator to hold the key in depressed position during the responsive operations of the machine, a ratchet-bar 140 (Figs. 2 and 10) is fixed to the rear end of the lever 116, in 15 position to coöperate with a pawl 142. This pawl is mounted on a pivot 144 on the frame of the machine, and has a depending arm with a beveled extremity 146. Coöperating with this extremity is a spring-pressed plunger 148. 20 This plunger acts, when the parts are in the position of Fig. 2, to maintain the pawl in coöperative engagement with the ratchet-bar, but when the pawl is swung rearwardly to an extent greater than that necessary to permit it to ride over the ratchet-teeth, the plunger 148 may engage the rear surface of the extremity 146, and thereafter the pawl will be held out of engagement with the ratchet-teeth. This extreme swinging movement of 25 the pawl is caused by a projection 150, at the lower end of the ratchet-bar, which is brought into engagement with the pawl when the lever 116 has been raised to its extreme upward position, in which the rod 110 is disengaged from the highest shoulder 122 on 30 the segment 120. This action occurs when the last of the keys 14 is pressed, this key being designated as the "Finish" key and being pressed always at the completion of the 35 operation of building a heel.

The result of the arrangement just described is to cause the pawl to retain the lever 116 in any position to which it has been raised until the finish key has been pressed, 40 and then to permit the lever and the rod 110 to fall to their original lowermost position, in which the rod 110 may be engaged by the first and lowermost of the shoulders 122. The shoulders are so located that when the 45 rod 110 is disengaged from the last and highest shoulder the gear-segment 92 has been brought into position to coöperate with the pinion 96, while the Geneva-stop pinion 94 has reached the end of the coöperating teeth 50 and surfaces 90 on the cylinder, and accordingly the cylinder is given a rapid and continuous rotative movement by the pinion 96, to bring the slide 80 and the lift-receptacles back to their original position, this movement being arrested by engagement of the 55 first stop-shoulder 122 with the rod 110 when the parts are in a position such that the first or No. 1 lift-receptacle is in coöperative relation with the transfer-mechanism. When 60 the lever 116 descends to this lowermost

point, as just described, the lower end of the ratchet-bar 140 engages the lower extremity 146 of the pawl and swings the pawl back into operative position, so that it may again act to retain the lever 116 after its next succeeding rising movement.

After each selective operation an operative movement of the transfer-mechanism must be produced, and this is accomplished through the action of the Horton clutch 75 before referred to. This clutch (see Figs. 3 and 6) has an outer member 154 integral with the gear 62, and an inner member 156 keyed to the countershaft 64, these members being connected, in the usual manner, by 80 friction-rollers 158. As clutches of this kind are well known, the construction of the present clutch is not completely illustrated, but it will be understood that the clutch is provided with the usual rotatable controller 85 160 having a stop-lug 162 which coöperates with a detent-arm 164, as shown in Fig. 3. The detent-arm is mounted to rock on a stud 166 (Figs. 3 and 7) fixed on the frame of the machine, and is provided with a lug 90 168 perforated to loosely embrace a screw 172 rising from the frame of the machine. A spring 170 coiled about this screw presses the lug downwardly, so as to swing the detent-arm downwardly into operative position, this downward movement being limited by a collar 174 on the screw. When the detent-arm is momentarily raised so as to disengage it from the stop-lug 162, the controller 160 permits the clutch to connect the 95 shaft 64 with the gear 62, so that a rotation may be imparted to the shaft, this rotative movement being arrested, however, when the stop-lug again engages the detent-arm. This single rotation, through the action of 100 the crank 66, causes the transfer-mechanism to perform its cycle of operations as before described.

The action of the Horton clutch is controlled automatically so as to occur at the 110 completion of the selective movement before described. For this purpose the forward end 176 of the slide-rod 110 is arranged to coöperate with a lever 178 (Figs. 3 and 7) which is mounted to swing loosely on the 115 stud 166. This lever carries a pivot-stud 184, upon which a hook-shaped latch 182 is mounted in position to coöperate with a trip-lug 188 projecting upwardly from the detent-arm 164. A spring 190, attached to 120 a pin projecting downwardly from the hub of the lever 178, acts, when the rod 110 moves rearwardly, to rock the lever in a direction to permit the latch 182 to ride over and operatively engage the trip-lug 188. 125 Upon a succeeding return-movement of the rod 110 it swings the lever 178 forwardly, thus causing the latch to swing the trip-lug forwardly and thus raise the detent arm. The latch is provided, however, with a lug 130

192 which depends into position to engage a stop-screw 194 on the frame of the machine, so that at the completion of the movement of the lever 178 the latch is raised 5 from engagement with the trip lug, thereby permitting the detent-arm to be depressed again into position to disengage the Horton clutch.

- In some cases it is desirable to build a 10 heel having two or more adjacent lifts of the same size, and the present machine is so constructed that lifts may be taken successively from the same supply receptacle. In such case the Horton clutch must be caused 15 to actuate the transfer-mechanism without any intervening operations of the selecting-mechanism. For this purpose supplementary trip-mechanism is provided, which is operable independently of the slide-rod 110. 20 The rock-shaft 126, on which the key-levers are mounted, is provided with an arm 222 fixed to its left-hand end, as shown in Fig. 3, and a similar arm at its right-hand end. A rod 224 extends between these arms, in 25 position to be engaged by the lifter-arms 128 when they are swung forwardly in consequence of the depression of the key-levers. By such engagement the rod and the arms are swung forwardly, or to the right as seen 30 in Fig. 3. This movement is communicated, by the arm 222, to a trip-bar 226 of which the rear end is pivoted to the arm, and this bar is provided with a shoulder 228 (see dotted lines Fig. 3) adapted to coöperate 35 with the trip-lug 188 and thus to raise the detent-arm. The trip-bar has a beveled surface 230 on its forward end, which rests upon a disk 232 fixed on the frame of the machine, so that the movement of the bar causes it also 40 to swing upwardly and thus disengage the shoulder 228 from the trip-lug after sufficient movement has been imparted to the latter to trip the Horton clutch. When the key lever, by which the parts just described have been 45 actuated, is released, the trip-bar 226, the arm 222 and the rock-shaft are returned to normal position by a spring 233 connected between a pin on the inner side of the bar 226, and a pin on the frame (see Fig. 3). 50 The disk 232 is mounted eccentrically and fixed in position by a nut 234, so that it may be rotated for the purpose of adjustment.
- When the selecting-mechanism is in operation it is obviously necessary to prevent 55 the supplementary trip-mechanism from throwing the transfer-mechanism into operation at the moment of depressing the key-lever, and for this purpose the lever 178 is provided with a forwardly projecting finger 236 extending below the forward end of the trip-bar 226 (see Fig. 3) so that when the lever 178 swings rearwardly, in consequence of a sliding movement of the rod 110, the trip-bar is lifted out of operative 60 relation with the trip-lug 188. To permit

this action to occur before the trip-bar can be moved sufficiently to cause it to act upon the trip-lug, sufficient lost motion is provided between each of the lifter-arms 128 and the rod 224 to permit the lifter-arms to 70 engage and raise the roller 133 and the lever 116, and thus cause the rod 110 to be moved rearwardly before the trip-bar is actuated. This clearance is shown in Fig. 9. It will also be apparent that when the finish-key is 75 depressed it is unnecessary to have any operative movement of the transfer-mechanism performed, and accordingly the lifter-arm corresponding to the finish-key is cut away, as shown by a dotted line in Fig. 3, 80 sufficiently to entirely avoid engagement with the rod 224.

For the reason just stated it is necessary also to prevent the Horton clutch from being tripped by the rod 110 on its return 85 movement after the finish-key has been pressed. For this purpose the latch 182 is provided with an arm 196 (Figs. 3 and 7) which projects upwardly to a position in which it will be engaged by the forward 90 end of the rod 110 when, but only when, this rod is in its lowermost position, namely, that position which it occupies when the rear end of the rod rests on the surface 152 of least diameter on the segment 120 (see 95 Fig. 2). In this case the rod, in moving forward, engages the arm 196, and this swings the latch upward out of operative position before any movement can be imparted by the latch to the trip-lug 188 and 100 the detent-arm; but upon a succeeding operation of the No. 1 key, or any other of the numbered keys, the rod 110 is raised clear of the upper end of the arm 196.

In case it is desired to have the operation 105 of the machine entirely automatic, the key-mechanism is operated mechanically by means of a drum 198 (Figs. 1, 3 and 6) mounted upon the countershaft 64 and provided with pins 200 arranged to coöperate 110 with depending arms 220 which are carried by the key-levers. These pins may be secured in the drum in such numbers and positions as to actuate the key-levers in a manner to select the lifts to the number and in 115 the order which may be desired. To rotate the drum 198 it is provided at one end, as shown in Figs. 2 and 6, with a ratchet-wheel 202 which is engaged by a hook-shaped pawl 204. This pawl is pivoted on a lever 208 120 of which the lower end is pivoted on the bracket 74. The upper end of the lever 208 bears against an eccentric 214 fixed on the countershaft 64. A spring 210 holds the pawl in engagement with the ratchet-wheel, 125 while a spring 216, coiled about a plunger 218 which is pivoted to the lever 208, holds the lever in engagement with the eccentric. This arrangement is such that at each rotation of the countershaft, produced by the 130

Horton clutch in the performance of the transferring operation, the drum is rotated through one-tenth of a rotation, and the pins 200 are so spaced that this movement is sufficient to bring them successively into engagement with one or another of the arms 220. When the automatic operation is not desired the spring 210 may be disengaged from the pawl, so as to throw the pawl out of operative engagement with the ratchet-wheel. Of course, if desired to construct the machine for automatic operation only, the key-levers 124 and finger-keys 14 may be omitted, since these parts of the key-mechanism are useful only for manual control.

After a heel-pile has been completely built on the holder 11 it is automatically released therefrom, and ejected from the machine, by means which will now be described. A plunger 240 (Fig. 4) is mounted to slide through the holder, and is pressed forwardly by a coiled spring 242. This plunger, or clearer, is actuated by an ejector comprising an arm 244 which is fixed to the forward end of a rock-shaft 246 (Fig. 2) journaled in the frame of the machine. An arm 248 at the rear end of the rock-shaft is connected, by a link 250, with a lever 252 (Fig. 1) which is pivoted, at its middle, on the frame of the machine, and which carries a roller 254 at its lower end. This roller engages a cam-path 256 formed in the right-hand end of the cam-cylinder 86, and this cam-path has a portion, shown in dotted lines in Fig. 1, arranged to move the cam-roller and cause the arm 244 to be swung to the right, (viewing Fig. 1), at a suitable time in the operation of the machine. The ejector-arm 244 is provided, on its rear surface, with a cam-projection 258 (Fig. 1) which engages the head of the clearer 240 and presses it rearwardly, thus pushing the heel-pile free from the points 50 on the holder 11. By a continuation of the same movement the U-shaped extremity 260 of the ejector-arm is caused to engage the heel-pile laterally, and knock it away from the machine.

The operation of the machine as a whole is as follows: Assuming that it is to be controlled manually, the operator presses the key corresponding to the size of the first lift which is to be employed, this lift being usually the largest in the heel-pile. The selecting-mechanism thereupon operates, by a partial rotation of the cam-cylinder, to move the supply-receptacles automatically into position in which the proper receptacle is in position for the operation thereon of the transfer-mechanism. Upon the completion of this movement the Horton clutch is automatically thrown into operation, to cause the transfer-mechanism to move rearwardly to the selected receptacle, withdraw-

a lift therefrom, and then move forwardly, at the same time swinging the lift downwardly and forwardly into a vertical position, and finally to press this lift against the points of the holder 11. The transfer-mechanism then comes to rest in an intermediate position, this position being the same as that shown in Fig. 2, although in that figure the transfer-mechanism is shown as in the course of the transferring operation, a lift being shown in place on the plate 23.

If it be desired to use in the heel two lifts of the same size adjacent each other, the operator may then press the same key again, in which case there will be no operation of the selecting-mechanism, but the transfer-mechanism will at once operate again to transfer a second lift. In cases where it is desired to use two lifts from the first receptacle, the means for throwing the paste-roller out of operation cannot be employed, as in this case it is necessary to apply paste to the second of the two lifts, but where only a single lift from the first receptacle is required, this throw-out mechanism may be used. Assuming that a single lift has been withdrawn from the first receptacle, and that it is desired then to use a smaller lift, the operator presses the key corresponding to the size of this second lift, which may be either the No. 2 key or any succeeding key, according to circumstances. The selecting and transferring operation is then repeated as before, and two or more of this second size of lift may be delivered to the heel-pile if desired, according to the form of the heel which is to be produced. After the last desired lift has been selected and transferred, the operator presses the finish-key, whereupon the final rotation is imparted to the cam-cylinder, which causes the ejecting-mechanism to be operated, and also returns the receptacles to their original or normal position, in which the No. 1 receptacle is ready to have a lift withdrawn from it at the commencement of a second heel-building operation.

When the machine is to be operated automatically the foregoing operations occur in the same manner and order, except that manual manipulation of the keys is obviated by the action of the automatic selecting-mechanism, and in this case the machine may operate continuously to produce heels until thrown out of operation, lifts being supplied to the receptacles as may be required to maintain the supply in them.

The present machine has been illustrated as arranged to operate upon what are technically known as heel-lifts, such lifts being pieces of leather or other sheet-material which have been died out to the curvilinear shape of a shoe heel. For this reason the machine has been described as operating upon "heel-lifts," but it will be understood

- that the pieces of material from which a heel-pile is formed by the present machine need not necessarily have this particular form, but may be blanks or thicknesses of various forms suitable for composing a heel-pile from which a heel may subsequently be formed, the modifications in the form of the parts of the machine necessary to accommodate blanks of other forms being such as may readily be made by those skilled in the art; and accordingly it will be understood that in the following claims the term "lift" or "heel-lift" is not intended to limit the invention to a machine adapted only for operating upon blanks or thicknesses of heel material of the particular form and character technically designated by this term.

It will be clear to those skilled in this class of machines, with the general objects of the present invention in view, that changes may be made in the details of structure, the described and illustrated embodiment thereof being intended as an exploitation of its underlying essential, the features whereof are definitely stated in their true scope in the claims herewith.

What is claimed as new, is:—

1. A heel-building machine, having, in combination, means for holding supplies of lifts of graded characteristics; and means for selecting lifts therefrom, in a variable order other than that in which the lifts are graded, and for assembling the lifts in a heel-pile.

2. A heel-building machine, having, in combination, means for holding supplies of lifts of graded characteristics; and automatic means for selecting lifts therefrom, in a predetermined order different from that in which the lifts are graded, and for assembling the lifts in a heel-pile.

3. A heel-building machine, having, in combination, a plurality of containers for lifts; a carrier adapted to remove the lifts from said containers; and selective means for controlling the removal operation, to determine the sequence in which the carrier removes the lifts.

5. A heel-building machine, having, in combination, a plurality of containers for lifts; a carrier adapted to remove lifts from said containers; and automatic selective means, for controlling the removal operation, to determine the sequence in which the carrier removes the lifts.

6. A heel-building machine, having, in

combination, a plurality of containers for lifts, a holder on which the heel-lifts may be assembled in the form of a heel; a carrier adapted to remove lifts from the containers and to assemble them on the holder; and means for selectively determining the containers from which the carrier removes the several lifts in sequence. 70

7. A heel-building machine, having, in combination, means for holding a stack of horizontally disposed lifts; a holder upon which the lifts may be assembled in a vertical position into a heel-pile; and a carrier constructed and arranged to remove lifts successively, edgewise, from the stack and to 75 turn the lifts into vertical position and apply them to the holder in stacked formation.

8. A heel-building machine, having, in combination, means for holding a stack of horizontally disposed lifts; a holder upon which the lifts may be assembled in a vertical position; a carrier constructed and arranged to remove lifts successively, edge-wise, from the stack and to turn the lifts into vertical position and apply them to the 80 holder; and means for applying adhesive to the lifts before their application to the holder.

9. A heel-building machine, having, in combination, means for holding a supply of lifts of graded characteristics; a holder on which the lifts may be assembled in the form of a heel-pile; and means for automatically and selectively discharging lifts from said supply to said holder, in a pre-determined sequence other than that in which the lifts are graded. 95

10. A heel-building machine, having, in combination, means for holding a supply of lifts of graded characteristics; means for removing lifts therefrom and assembling them in the form of a heel-pile; and key-mechanism for selectively controlling the removal to determine the order in which the lifts are assembled. 100

11. A heel-building machine, having, in combination, a series of containers for lifts; a holder on which the lifts may be assembled; a carrier; means for moving the containers past the carrier to bring it into operative relation with the containers selectively; and means for moving the carrier from the containers to the holder to transfer lifts thereto. 110

12. A heel-building machine, having, in combination, a series of containers for lifts; a holder on which the lifts may be assembled; a carrier; means for moving the containers past the carrier to bring it into operative relation with the containers selectively; means for moving the carrier from the containers to the holder to transfer lifts thereto, and means for applying adhesive to the lifts on the carrier during the transferring movement. 120

13. A heel-building machine, having, in combination, means for holding a stack of horizontally disposed lifts; means for removing a lift singly from the stack, with an edgewise movement, and for thereafter turning it from its original horizontal position and pressing it against a previously abstracted lift, and means for applying adhesive to the upper surface of each lift prior to such turning movement.
14. A heel-building machine, having, in combination, a series of containers for lifts of graded characteristics; and means for removing a series of lifts from the containers, said series comprising a single lift from each of certain of the containers and a plurality of lifts from certain other of the containers, and for assembling the lifts so removed in a predetermined order.
15. A heel-building machine, having, in combination, a container for holding lifts; a holder on which the lifts may be assembled in the form of a heel-pile; a carrier adapted to support a lift by engagement with its edges and one face; and means for moving the carrier in a direction to first remove a lift edgewise from the container and then force it toward the holder in a direction normal to the plane of the lifts in the pile.
16. A heel-building machine having, in combination, a plurality of containers for holding lifts of different characteristics; and selective means for removing lifts from any of said containers in any desired sequence.
17. A heel-building machine having, in combination, a plurality of containers for holding lifts; a carrier adapted to remove a single lift from any one of the containers; and selective means for causing relative movement between the carrier and the containers to bring the carrier into operative relation with any predetermined container irrespective of the relative arrangement of the containers.
18. A heel-building machine having, in combination, a vertical container for holding a stack of lifts disposed one above the other in a horizontal plane; and means acting successively upon the stacked lifts for seizing and removing the lifts one by one from one end of the stack and, while retaining control thereof, turning them through a right angle into a vertical plane.
19. A heel-building machine having, in combination, a vertical container for holding a stack of lifts disposed one above the other in a horizontal plane; and means acting upon the stacked lifts for removing the lifts from one end of the stack and stacking the removed lifts in an angularly positioned plane to form a heel-pile.
20. A heel-building machine having, in combination, a container for holding a plu-
- rality of lifts stacked in a predetermined plane; a receiving-member disposed substantially normal to said container in which the lifts may be stacked in a plane substantially normal to the initial stacking plane; and means acting progressively upon the lifts in one end of said container for turning said lifts through a right angle and stacking them in said receiving member to form a heel-pile.
21. A heel-building machine having, in combination, a plurality of containers for holding lifts of different characteristics; a receiving member on which the lifts may be assembled to form a heel-pile; and selective means for successively transferring the lifts from said containers to said receiving member in any desired sequence.
22. A heel-building machine having, in combination, a plurality of containers for holding lifts; and means including a key-mechanism for selectively removing lifts from any of said containers in any desired sequence.
23. A heel-building machine having, in combination, a plurality of containers for holding lifts; means including a key-mechanism for selectively removing lifts from any of said containers in any desired sequence; and automatic means for controlling the operation of said key-mechanism.
24. A heel-building machine having, in combination, a row of containers for holding lifts; means for removing lifts therefrom and assembling them in the form of a heel-pile; means for effecting relative movement in the line of said row of containers between said containers and said removing means to bring the removing means into operative relation with any container; and selective means embodying a key-mechanism for determining the relative movement of said containers and said removing means and the sequence in which the lifts are assembled.
25. A heel-building machine having, in combination, means for holding lifts, a receiving member to which the lifts are transferred; a reciprocating carrier for successively transferring the lifts from said holding means to said receiving member to form a heel-pile; and means acting upon said carrier for angularly turning the lifts during its transferring movement.
26. A heel-building machine having, in combination, a container for holding lifts; a receiving member to which the lifts are transferred; a reciprocating carrier for successively transferring the lifts from said container to said receiving member and stacking them to form a heel-pile; means for rotating said carrier to angularly turn the lifts during its transferring movement; and means for ejecting the heel-pile so formed from said receiving member.
27. A heel-building machine having, in combination, a receiving member disposed substantially normal to a stack of lifts, and means for turning the lifts through a right angle and stacking them in said receiving member to form a heel-pile.

combination a series of containers for lifts; means for removing lifts from said containers; and selective means for causing said removing means to successively take one or 5 more lifts from any of said containers in any desired sequence.

28. A heel-building machine having, in combination, a movable row of containers for lifts, and adapted to be actuated in the 10 direction of the row; a stationary lift-receiving member disposed in front of said row of containers; and a movable carrier adapted to be reciprocated in a line normal to the direction of actuation of said row of 15 containers for transferring the lifts from said containers to said receiving member.

29. A heel building machine having, in combination, a plurality of containers for lifts, means for successively removing lifts, 20 one at a time, from any particular container during the formation of a single heel, and means for determining the particular container upon which the removing means shall act.

30. A heel building machine having, in combination, a plurality of containers for lifts, and means for removing from the containers a sufficient number of lifts to form a heel, said means being constructed and arranged to remove a plurality of said lifts in immediate succession from any particular container.

31. A heel building machine having, in

combination, a plurality of containers for lifts, and means for removing from the containers a sufficient number of lifts to form a heel, said means being constructed and arranged to remove a plurality of said lifts in immediate succession from each of one or more of said containers. 35

32. A heel building machine having, in combination, a plurality of containers for lifts, means for successively removing a plurality of lifts from one of the containers, and automatic means for causing said removing means to act upon the lifts in another container during the formation of a single heel. 40

33. A heel building machine having, in combination, a plurality of containers for lifts, means for removing lifts therefrom and assembling them in a pile, and means for shifting the operation of said removing means from one container to another container and for causing said removing means 50 to act successively upon one or more of said containers during the formation of a single heel. 55

34. A heel building machine having, in combination, a container adapted to retain a stack of heel lifts, means for successively removing a plurality of heel lifts from said stack and assembling them to form a heel-pile, and means for securing together the component lifts of said heel-pile. 60

THOMAS LUND.
